UNITED STATES PATENT OFFICE.

KNUD DE LONY, OF BRIDGEPORT, CONNECTICUT, ASSIGNOR TO JOHANNES SCHIOTT, OF GREENS FARMS, CONNECTICUT.

METHOD OF INCREASING THE EFFICIENCY OF INTERNAL-COMBUSTION MOTORS.

1,212,917.

Specification of Letters Patent. Patented Jan. 16, 1917.

Application filed October 29, 1915. Serial No. 58,616.

To all whom it may concern:

Be it known that I, KNUD DE LONY, a subject of the King of Denmark, residing at the city of Bridgeport, county of Fairfield, 5 State of Connecticut, United States of America, have invented certain new and useful Improvements in Methods of Increasing the Efficiency of Internal-Combustion Motors; and I do declare the following to be 10 a full, clear, and exact description of the invention, such as will enable others skilled in the art to which it appertains to make and use the same.

My invention relates to certain improvements in and relating to internal combustion motors and has for its object to increase the efficiency of the motor by utilizing the heat in a cylinder which heat is usually wasted by the exhaust and cooling of 20 the products of combustion.

In the accompanying drawing Figure 1 is a theoretical indicator diagram of a motor of the Diesel type during a working stroke when my invention is utilized, the ordinate 25 of the part of the pressure curve which runs parallel with the abscissa axis being determined by the pressure of the air forced into the cylinder. Fig. 2 illustrates the corresponding indicator diagram for the compressor. Fig. 3 is a view, similar to Fig. 1, of an internal combustion motor of the four cycle type during a working stroke with my invention applied. Fig. 4 illustrates the indicator diagram for an expansion cylinder 30 with four times the volume of the combustion cylinder. Fig. 5 is a diagrammatic view in elevation of a four cylinder four cycle internal combustion motor showing the application of my improvement. Fig. 6 35 is a plan view of the construction shown at Fig. 5, and Fig. 7 is a diagrammatic view in elevation, with a projected theoretical indicator diagram, of a cylinder and working piston such as may be utilized when the 40 45 whole expansion takes place in the combustion cylinder.

Similar numerals of reference denote like parts in the several figures of the drawing.

My invention, broadly speaking, consists 50 in forcing or introducing into a cylinder, during a working stroke of the piston and after combustion is completed, compressed air or other gaseous mixture of a lower temperature than that of the gases then expanding within the cylinder.

The comparatively cool air or other gaseous mixture is immediately heated by the expanding gases and continuously supplies the deficiencies in pressure within the cylinders during the working stroke of the piston, or, in other words, acts to automatically maintain the expansion curve at constant pressure during that part of the working stroke of the piston which follows immediately after the initial introduction of such air or gaseous mixture.

The obtainable energy within the cylinders depends largely upon the difference in temperatures between the expanding gas and the air that is forced into the cylinders, and the increased energy made available can be utilized in various ways some of which I will now describe.

Referring to Figs. 5 and 6, 1, 2, 3, and 4, 5 represent the cylinders of a gas engine, and 5 is an expansion cylinder closed at the ends, the combustion chambers of the cylinders 2 and 3 being in connection with the upper part of the cylinder 5 through the medium of branch pipes 6, while the combustion 80 chambers of the cylinders 1 and 4 are in connection with the lower part of the cylinder 5 through the medium of branch pipes 7.

8 is any suitable air pump provided with 85 outlet 9 which leads into a reservoir 10 within which latter the air is held in compressed condition owing to the action of the pump.

11 are suitable valve controlled connections between the reservoir 10 and the combustion chambers of the cylinders 1, 2, 3, and 4.

During the working strokes of pistons 90 within their cylinders, the valves controlling the supply of compressed air to the combustion chambers of these cylinders will be operated to effect the introduction of a predetermined amount of air into said chambers, the pressure within the reservoir 100 10 being, of course, greater than that within the chambers, while the temperature of the air is considerably lower than that of the expanding gases within these chambers. As soon as the comparatively cold air has been 105 delivered within these combustion chambers, said air will be immediately expanded by the action of the heat within said chambers, and since the pressure within said chambers would ordinarily be decreasing, 110

owing to the constantly increasing volumes of the chambers, the introduction and expansion of the air will constantly supply these deficiencies in pressure, so that the expansion line (curve) will be maintained at constant pressure during a material part of the working stroke of the piston.

During the introduction of cold air within a cylinder, such as has been described, a substantially constant pressure will have been maintained within such cylinder, and on the upward stroke of the piston of said cylinder the contents of such cylinder will expand into the expansion cylinder 5 above piston 16 therein, the latter at that time being at the end of its upward stroke, and as the contents of such cylinder act on the piston 16 the latter will be driven downwardly, thereby still further assisting in the revolution of the crank shaft. The admission of the contents of the cylinders 1, 2, 3, and 4, within the cylinder 5 is automatically controlled by means of suitable valves not shown herein. As the piston 16 moves downwardly it will expel the gases previously admitted below the piston from another cylinder, while the next upward movement of this piston 16 will expel the gases admitted from a subsequent cylinder. After the piston 16 has reached its lowest position, the piston of a combustion cylinder will be at the lowest limit of its working stroke, and on the upward movement of this last named piston the contents of said cylinder will expand into the bottom of the cylinder 5 immediately below the piston 16 and will cause the latter to be forcibly elevated, thereby likewise further assisting in the revolution of the crank shaft.

The matter of valves between any of the parts is very ordinary and these valves have not been illustrated because they form no part of this invention.

As the contents of the cylinders 1, 2, 3, and 4, are expanded into the larger cylinder 5, the temperature and pressure will fall according to well known governing rules, and by proper determination of dimensions I can utilize the contents of the cylinders down to approximately the pressure of the atmosphere, and the temperature of these contents will then have been reduced accordingly.

From the foregoing description it will be clear that, on account of the fact that the piston in the expansion cylinder has a larger area, it will move downward while the smaller piston in a combustion cylinder moves upward, and, as the volume for the expansion increases, the pressure and temperature will decrease. When the piston in the expansion cylinder is at the end of a stroke the contents of such cylinder that are exhausted have no appreciable pressure or temperature beyond that of the atmosphere.

Since the piston in the expansion cylinder receives impulses above and below the same from the expansion of the contents of combustion cylinders, it will be clear that such piston will have two working strokes to each revolution of the crank shaft.

In Figs. 1, 2, 3, and 4, the same scale has been used for pressure and volume. Only the effective work has been shown in section. Therefore, it will be evident that the work during one stroke is found by adding the sectioned areas in Figs. 1 and 4, and, by deducting the sectioned areas of Fig. 2, which is the compressor work, it is seen how the efficiency of the motor is increased.

Referring particularly to Fig. 7, I have shown a cylinder 17 that is elongated so that the piston 18 therein may have a longer stroke, this particular construction being utilized where the whole expansion takes place in the combustion cylinder itself, instead of utilizing the expansion cylinder to coöperate with a combustion chamber in enlarging the volume for such expansion. In this construction shown at Fig. 7, during the working stroke of the piston, the cold air is introduced within the combustion chamber, giving the results hereinbefore set forth, and the following upward stroke of the piston will cause the contents of the combustion chamber to be ejected through any suitable exhaust; the next downward stroke of the piston will effect the introduction of the explosive mixture within the combustion chamber.

A cylinder like that illustrated at Fig. 7 may be utilized as a Diesel type of motor, in which instance, after the exhaust stroke of the piston, as just described, the next downward stroke would draw into the cylinder a charge of fresh air, while the following upward stroke of the cylinder would cause this air to be exhausted until the piston reached the line *a*, whereupon the rest of the piston stroke would compress the air, thus giving to the latter a very high temperature, and while the air is thus compressed and is at this high temperature, the oil would be injected into the compressed air, and the combustion of the oil would create the usual expansion to cause the working stroke of the piston, and during such stroke the cool air would be introduced into the combustion chamber, thus maintaining the pressure as before described.

It will, therefore, be readily understood that my invention is applicable to engines operating on either the Otto or Diesel cycles.

I claim:

1. The method of increasing the efficiency of an internal-combustion motor in which the combustion begins when the volume is predetermined and the pre-compression at a maximum, which consists in introducing air

under pressure into the working space of the cylinder after the combustion is completed, thereby maintaining the pressure substantially constant during such introduction of 5 air, and thereafter, in order to accomplish further work, expanding the gases adiabatically.

2. The herein-described process of operating internal-combustion engines, which 10 consists in compressing the charge, then igniting the charge while under its maximum compression, introducing relatively cool air under pressure into the working space of the cylinder after completion of 15 combustion and during the working stroke of the piston, whereby the pressure within the cylinder will not be decreased during the introduction of such air while at the same time the cylinder contents will be cooled, 20 and thereafter expanding the gases adiabatically to atmospheric pressure, or thereabout, for the performance of additional work.

3. The herein-described process of operating 25 internal combustion engines wherein pre-compression is effected by the working piston to a predetermined volume and maximum degree, which consists in igniting the fuel within said volume, introducing relatively cool air under compression into the 30 working space of the cylinder after combustion is completed and thereby maintaining the pressure substantially constant within the cylinder during the introduction of such 35 air, and finally adiabatically expanding the cylinder contents to atmospheric pressure, or thereabout, in the performance of other work, thereby increasing the expansion ratio and the efficiency of the motor.

4. The herein-described process of operating 40 internal combustion engines of the Otto or Diesel type, which consists in introducing highly compressed, relatively cool air into the working space of the cylinder after the 45 charge is combusted and thereby maintaining the working pressure within the cylinder during the introduction of such air, and thereafter adiabatically expanding the cylinder contents to atmospheric pressure, or 50 thereabout, in the performance of other work, thereby increasing the expansion ratio and the efficiency of the motor.

5. The herein-described process of operating 55 internal combustion engines working on the Diesel or Otto cycle, which consists, after combustion of the fuel is completed, in maintaining the pressure substantially con-

stant for a predetermined time and also in increasing the expansion ratio, by introducing relatively cool compressed air into the 60 working space of the cylinder for so long a time as pressure is to be maintained, and thereafter adiabatically expanding the cylinder contents to atmospheric pressure, or thereabout, in the performance of further 65 work.

6. The method of increasing and utilizing the thermal efficiency of internal combustion engines wherein combustion commences when the volume is predetermined and pre-compression at its maximum, which consists in increasing the normal expansion ratio by introducing air under pressure into the working space of the cylinder after combustion is completed and thereby maintaining 75 the working pressure substantially constant during such introduction of air, and thereafter expanding the mixed gas to atmospheric pressure, or thereabout, to accomplish further work.

7. The method of increasing the thermal 80 efficiency of internal combustion engines wherein combustion commences when the volume is predetermined and pre-compression at its maximum, which consists in introducing air under pressure into the working space of the cylinder after combustion is completed, and thereafter expanding the products of combustion adiabatically to atmospheric pressure, or thereabout, to accomplish further work, whereby the working pressure is maintained substantially constant during the introduction of such air and the ratio of expansion increased.

8. The method of increasing the thermal 85 efficiency of internal combustion engines wherein combustion commences when the volume is predetermined and the pre-compression at its maximum, which consists in introducing air under pressure into the cylinder after combustion is completed and during the working stroke, thereby maintaining the pressure substantially constant during the introduction of such air, and thereafter expanding the gas adiabatically 90 to atmospheric pressure, or thereabout, to further increase the efficiency of the motor.

In testimony whereof I affix my signature in presence of two witnesses.

KNUD DE LONY.
